JOSEPH E. PERRAULT, OF WALTHAM, MASSACHUSETTS, ASSIGNOR TO JUDSON L. THOMSON MFG. CO., A CORPORATION OF MAINE.

MACHINE FOR SETTING RIVETS.

No. 879,896.

Specification of Letters Patent.

Patented Feb. 25, 1908.

Application filed July 31, 1907. Serial No. 386,349.

To all whom it may concern:

Be it known that I, JOSEPH E. PERRAULT, a citizen of the United States, residing at Waltham, in the county of Middlesex and 5 State of Massachusetts, have invented new and useful Improvements in Machines for Setting Rivets, of which the following is a specification.

This invention relates to machines for 10 setting rivets or the like in leather or other sheet material.

The object of the invention is to provide an improved means for guiding the rivet from the raceway to the carrier or holder in 15 which it is held prior to being driven in the stock by a suitable driver. In machines of this class in which rivets or the like are employed which are fed from a hopper down a raceway to a carrier or other receptacle in 20 which the rivet is placed before being driven, the rivet is very liable, in passing from the raceway to said carrier, to tip over and enter the carrier with the shank of the rivet projecting upwardly instead of down- 25 wardly as is desired. This is especially liable to occur when a rivet has a large head and short shank, and it is one of the objects of this invention to provide a device which shall prevent the rivet from tipping over, as 30 hereinbefore set forth, and to hold the same in correct position from the time it arrives at the lowermost end of the raceway until it enters the carrier from the raceway with its head uppermost and leave the same in 35 said carrier in proper position to be driven into the stock by the driver.

It is further the object of this invention to provide a device of the character set forth which may be adapted to rivets having 40 different sized heads and different length shanks and it is also to be understood that the device of this invention may be adapted to articles other than rivets, such as tacks, nails, lacing hooks, boot buttons, et cetera.

45 This invention is similar in many respects to another invention made by me and set forth in a co-pending application Serial No. 358,614, filed February 21, 1907, but differs from said invention in that the guide finger 50 is so formed and actuated that the lower end of said guide finger is adapted to contact with the top of the head of the lowermost rivet while the same is at the bottom of the raceway and before it leaves the raceway to 55 enter the carrier, said finger being also

adapted to guide and prevent said rivet from tipping over as it passes from the raceway to the carrier. The advantage gained by this construction and operation of the rivet guiding finger as compared with that 60 set forth in said co-pending application for Letters Patent is that the rivets, instead of being fed in a continuous row down a raceway for a portion of the length of the raceway and then separated one by one from 65 said column of rivets in the raceway to be dropped down another portion of the same raceway one by one and then pass from said last named raceway to the rivet carrier, are adapted to stand in a column in a single 70 raceway with the lowermost rivet in the raceway held and controlled by said finger from the time it leaves the raceway until it arrives in its position in the carrier after leaving the raceway. The next rivet to the lower- 75 most rivet is prevented from passing out of the lower end of the raceway by the driver which is so timed as to close the lower end of the raceway in time to prevent said second rivet from passing out thereof. 80

The invention consists in the combination and arrangement of parts set forth in the following specification and particularly pointed out in the claims thereof.

Referring to the drawings: Figure 1 is a 85 left hand side elevation of a rivet setting machine embodying my invention, the same being partly broken away and shown in section. Fig. 2 is an enlarged front elevation, broken away to save space in the drawings, 90 of the raceway and mechanism for carrying the rivets from said raceway to the material in which they are to be driven and driving mechanism by means of which said rivets are inserted in said material and clenched 95 therein. Fig. 3 is a side elevation viewed from the right of Fig. 2. In Figs. 2 and 3 the rivet carrier and driver are shown raised. Fig. 4 is a front elevation similar to Fig. 2 with the driver and carrier lowered into position to set the rivet in the leather. Fig. 5 is a sectional elevation taken on line 5—5 of Fig. 3 looking toward the right in said figure, showing a portion of the raceway, the rivet carrier, the guide finger and the driver, the 105 driver being shown in its uppermost position. Fig. 6 is a sectional elevation similar to Fig. 5, showing the driver part way down and just about to contact with the head of the rivet, while the guide finger is shown thrown 110

back by the driver to the left in said figure of the chamber in which the rivet is located in the carrier.

Like numerals refer to like parts throughout the several views of the drawings.

In the drawings, 20 is the frame of the machine, 21 a driver slide adapted to slide in ways 22 and having a driver 23 fast thereto. The driver slide 21 and driver 23 form, in effect, one piece and will be so considered in the following specification and claims. Said driver 23 has a reciprocatory motion imparted thereto by a lever 24 connected to said driver by a link 25, said lever 24 being pivoted at 26 to the frame 20. The lever 24 is rocked on said pivot 26 by means of a foot-treadle and spring (not shown in the drawings) said lever being connected to said treadle by means of a link 27. The downward motion of the rear end of the lever 24 is limited by a stop 28 having screw-threaded engagement with the frame 20 whereby the upward movement of the driver slide 21 and driver 23 is regulated.

The rivets 29, 29, 29 are fed from a hopper 30 to a raceway 31, consisting preferably of strips of steel fastened by screws to the outer face of a bracket 33. As the rivets descend the raceway the lowermost rivet in the raceway rests against the finger 63 when the parts are in the position illustrated in Fig. 5—that is, when the driver is up. Said finger is then moved, as hereinafter described, from the position illustrated in Fig. 5 to that illustrated in Fig. 6, remaining in contact with the head of the lowermost rivet 29 while it is at the lower end of the raceway and as it passes from the raceway to the carrier 36.

The carrier 36 consists of two side plates 49, 49, each provided in its upper end with a semi-annular groove 50 to receive the head of the rivet after it has passed from the raceway to said carrier, and beneath said semi-annular grooves, between the plates 49, 49, is a chamber 49'. Each of the plates 49, 49 is fastened to a flat spring 51, said flat spring being fastened by means of a bolt 52 and nut 53 to the carrier slide 54. The carrier slide 54 is adapted to slide in ways 55 formed in the head 56 of the frame 20 and is moved upwardly by a spiral spring 57, the lower end of which is fastened to a screw 58 fast to said carrier slide, the upper end of said spring being fastened by a screw 59 to the head 56. The material 60 into which the rivet is to be clenched is supported upon an anvil 61 which, in turn, is adjustably supported upon an arm 62 forming a portion of the frame 20.

The guide-finger 63 is pivoted at 64 to the carrier slide 54. The inner edge 65 of the finger 63 is inclined at an angle, at 66, to the driver 23 and bears against the lower end of that portion of the driver which I have designated as the "driver slide 21," as will be seen in Fig. 5, although it is immaterial which

portion of the driver said finger bears against, whether it be the slide 21 or the driver 23, or any other reciprocatory piece or movable piece actuated by said driver or by other suitable mechanism. The inner edge of said finger is held preferably in contact with the driver by a spiral spring 67, one end of which bears against the outer edge of the guide finger 63, the other end of said spring bearing against a plate 68 fast to the carrier slide 54. It will be noted that the guide-finger 63 is located in a slot or groove 69 extending longitudinally of the slide 54 and opening out of the inner face thereof. It will be seen that as the rivets 29 descend the lower portion 34 of the raceway and pass to the rivet carrier 36 they are very liable to tip and enter said carrier in an inverted or partly inverted position, as hereinbefore set forth. This is entirely obviated by the finger 63, the lower end 85 of which is located in the exact position to contact with the top of the head of the lowermost rivet while it is on the raceway and to move downwardly, allowing said rivet to slide freely from the lower part of the raceway into the carrier, but the motion of said finger is so timed that it will prevent the rivet from tipping over by reason of the lowermost end of said finger touching the top of the head of the rivet as it is passing from the raceway to the carrier and thus guiding it and keeping it in correct position to finally land with the head uppermost in the groove 50 in readiness . . . . . given, as hereinbefore described.

In feeding rivets of different sizes or forms it becomes necessary to adjust the guide-finger 63 so that the lower end thereof will approach the lower end of the groove 50 in the raceway more nearly or may be carried farther away therefrom, in order to correctly guide the rivets, as set forth, and in order that the free end of the finger may rest at exactly the right position upon the head of the rivet to control the same and prevent its tipping. To accomplish this adjustment of the guide-finger a variety of means may be employed without departing from the spirit of my invention. One very simple means is to limit the upward movement of the driver slide 21 and driver 23 by limiting the downward movement of the rear end of the lever 24 which can be conveniently accomplished by means of the stop-screw 28 (Fig. 1). I desire it to be distinctly understood that while I have illustrated and described, in this particular embodiment of my invention, the guide-finger 63 as having an inclined inner edge which bears against the lower end of the driver slide, it is evident that a variety of mechanical means might be used to rock the finger 63 upon its pivot to regulate and determine the position of the lower end of the finger while a rivet is located upon the lower edge of the raceway and subsequently while

said rivet is passing from the lower end of the raceway into the chamber in the rivet carrier, in readiness to be taken by the carrier to the stock and driven and clenched therein.

5 My improved guide-finger is capable of being used in such a manner as to eliminate as hereinbefore set forth, the necessity of feeding the rivets one by one by means of a stop-wheel, or other equivalent means, as in 10 the form of my invention illustrated in said application for Letters Patent, and this desirable result is attained entirely by the construction and operation of the guide-finger 63, extending said guide-finger entirely across 15 the chamber in the carrier, so that the end thereof shall rest against the top of the lowermost rivet in the raceway when the driver is raised.

The general operation of the mechanism 20 hereinbefore specifically described is as follows: Assuming the parts to be in the relative positions illustrated in Fig. 5, when the driver 23 is moved downwardly, the lower end of that portion of the driver indicated as 25 the driver slide abuts against the cam-shaped edge 66 of the finger 63, moving said finger toward the left, from the position illustrated in Fig. 5 to that illustrated in Fig. 6, allowing the lowermost rivet 29 to pass out from the 30 lower end of the raceway and enter the chamber provided in the carrier, as illustrated in Fig. 6. At the same time the driver 23 will descend a sufficient distance to form a block or stop to hold the rivets 29, 29 upon the 35 raceway until the driver is again brought downwardly after having set the first rivet in the stock and retreated to its uppermost position, as illustrated in Fig. 5. In its return movement it will be understood that 40 as the driver 23 moves upwardly, at of contact with the lowermost rivet in the raceway, the lowermost end of the finger 63 will be carried by the spring 67 beneath the lower end of the driver and above the chamber in 45 the carrier entirely thereacross and into contact with the lowermost rivet upon said raceway, which it will hold in position upon said raceway until the driver begins to move downwardly, when it releases the same.

50 By the construction hereinbefore described and illustrated, the operation of the feeding of the rivets is simplified and rendered more positive. In a quick running machine, it is very desirable that the lowermost rivet on the 55 raceway should be as near the carrier as possible, in order that the same may have time to be moved from the raceway to the carrier by the force of gravity. The quicker the running of the machine the shorter this distance must necessarily become and by the construction hereinbefore described and illustrated it will be seen that this distance from the raceway to the carrier is reduced to a minimum.

Having thus described my invention what 65 I claim and desire by Letters Patent to secure is:

1. In a machine for driving rivets and the like, a raceway, a carrier adapted to receive a rivet or the like from said raceway, a movable guide-finger, and means adapted to move said finger into contact with the top of of said rivet while it is on said raceway and to move said finger with said rivet and in contact with the head thereof while said rivet is 75 passing from said raceway to said carrier, whereby said rivet is prevented from tipping over.

2. In a machine for driving rivets or the like, a raceway, a carrier adapted to receive 80 a rivet or the like from said raceway, a movable guide finger adapted to engage the head of said rivet while it is on said raceway and as it passes from said raceway to said carrier, and adjustable means adapted to locate said 85 finger relatively to said raceway and carrier while said rivet is on said raceway.

3. In a rivet setting machine, a reciprocatory driver, a raceway, a rivet carrier provided with a chamber adapted to receive a 90 rivet, a finger pivoted to said carrier, the free end of said finger normally located above and extending across said chamber and adapted to contact with the top of the head of said rivet while it is on said raceway, the 95 inner edge of said finger inclined at an angle to and adapted to bear against said driver, and means to hold said finger in sliding contact with said driver, whereby the relative location of the free end of said finger to said 100 chamber and raceway may be varied, and said rivet prevented from tipping over.

4. In a rivet setting machine, a reciprocatory driver, a raceway, a rivet carrier provided with a chamber adapted to receive a 105 rivet, a finger pivoted to said carrier, the free end of said finger normally located above and extending across said chamber and adapted to contact with the head of said rivet while it is on said raceway, the inner edge of said finger inclined at an angle to and adapted to bear against said driver, means to hold said 110 finger in sliding contact with said driver, and a stop to limit the upward movement of said driver, whereby the relative location of the 115 free end of said finger to said chamber and raceway may be determined.

5. In a rivet setting machine, a reciprocatory driver, a raceway, a rivet carrier provided with a chamber adapted to receive a 120 rivet, a finger pivoted to said carrier, the free end of said finger normally located above and extending across said chamber and adapted to contact with the head of a rivet on said raceway, the inner edge of said finger 125 inclined at an angle to and bearing against said driver, means to hold said finger in sliding contact with said driver, and an adjust-

- able stop to limit the upward movement of said driver whereby the relative location of the free end of said finger to said chamber and raceway may be varied and determined.
- 5 6. In a machine for driving rivets and the like, a raceway, a carrier provided with a chamber adapted to receive a rivet or the like from said raceway, a guide-finger pivoted to said carrier, the free end of said finger 10 normally located above and outside said chamber, and means adapted to swing said finger entirely across said chamber and to move said finger with said rivet and in contact with the top of the head thereof while 15 said rivet is passing from said raceway to said carrier, whereby said rivet is prevented from tipping over.
7. In a rivet setting machine, a reciprocatory driver, an anvil, a raceway, a rivet carrier provided with a chamber adapted to receive a rivet, a finger pivoted to said carrier, the free end of said finger normally located 20 above said chamber and adapted to swing entirely thereacross into contact with the top of the head of said rivet when the same 25 is on said raceway, and means to hold said finger at all times in sliding contact with said driver, whereby said rivet is prevented from tipping over.
- 20 8. In a rivet setting machine, a reciprocatory driver, an anvil, a raceway, a rivet carrier provided with a chamber adapted to receive a rivet, a finger pivoted to said carrier, the free end of said finger normally located 30 above and extending entirely across said chamber and adapted to contact with the top of the head of said rivet when the same 35 is on said raceway, and a spring adapted to swing said free end laterally across said 40 chamber and to hold said finger at all times in sliding contact with said driver, whereby said rivet is prevented from tipping over.
9. In a rivet setting machine, a reciprocatory driver, an anvil, a raceway, a rivet carrier provided with a chamber adapted to receive a rivet, a finger, and a pivot fast to said carrier upon which said finger is mounted, said pivot located at all times above the lower end of said driver, the lowermost end of said finger terminating above said chamber and above the lowermost outlet end of 45 said raceway and adapted to contact with the top of said rivet when the same is upon and at the lower end of said raceway, whereby said rivet is prevented from tipping over. 50
10. In a machine for driving rivets and the like, a raceway, a reciprocatory carrier adapted to receive a rivet from said raceway, said carrier provided with a chamber, a reciprocatory driver, a guide-finger pivoted to said 55 carrier, the free end of said guide-finger normally located above said chamber and adapted to contact with said rivet when the same is at the lower end of said raceway, said finger having its inner edge inclined to and bearing against said driver, means to hold said finger in sliding contact with said driver, and means to stop said carrier during the upward movement of said driver, whereby the 60 relative location of said finger to said raceway and carrier is changed during the latter part of the upward movement of said driver. 65
- In testimony whereof I have hereunto set my hand in presence of two subscribing witnesses.
